UNITED STATES PATENT OFFICE.

THOMAS LEONARD, OF CHAMPAIGN, ILLINOIS, ASSIGNOR OF ONE-HALF TO
ALFONSO H. ISBELL, OF CHAMPAIGN, ILLINOIS.

GRAIN-CAR DOOR.

No. 854,049.

Specification of Letters Patent.

Patented May 21, 1907.

Application filed March 6, 1906. Serial No. 304,574.

To all whom it may concern:

Be it known that I, THOMAS LEONARD, a citizen of the United States, residing at Champaign, in the county of Champaign and State of Illinois, have invented a new and useful Grain-Car Door, of which the following is a specification.

This invention relates to the supplemental or inside guard doors employed in cars for carrying grain and like products or material, and has for its object to improve the construction and increase the efficiency of devices of this character.

With these and other objects in view which will appear as the nature of the invention is better understood, the invention consists in certain novel features of construction as hereafter fully described and claimed.

In the accompanying drawings forming a part of this specification and in which corresponding parts are denoted by like designating characters, is illustrated the preferred form of the embodiment of the invention capable of carrying the same into practical operation.

In the drawings Figure 1 is a sectional elevation of a portion of a grain car viewed from the inside, including one of the doorway openings, with the improved grain door attached. Fig. 2 is a section on the line 2--2 of Fig. 1. Fig. 3 is a sectional detail, enlarged on the line 3--3 of Fig. 1.

In the improved device is comprised a grain door in two sections, an upper section 10 and a lower section 11, of substantially equal size and hinged together at 12, to deflect inwardly or toward the interior of the car.

The door sections are constructed with sheet metal bodies 10--11, preferably of steel, with strengthening frames around the edges, the frames being of L shaped bars with the outer flat faces of the frame members at the hinged edges bearing against each other and firmly supporting the sections and preventing any tendency of the same to "buckle" or bend outwardly under the strains imparted thereto by the grain from within the car. The hinges 12 are constructed with their pintles disposed at a considerable distance from the adjacent or outer faces of the door sections, to still further brace and support the same from outward deflection.

The outward pressure of the grain when

the car is loaded is constant and severe, hence the importance of a door so constructed as to present a correspondingly strong resistance to such pressure. The device herein shown and described effectually resists this outward pressure, as will be obvious.

The lower door section 11 is formed with an opening 13 in the lower portion and the opening closed by small doors 14--15 hinged at 16--17 to the door section and with one door overlapping the other at their meeting edges, so that one pair of bolts or catches 18 may be employed to hold both doors in closed position, the catches being preferably operative simultaneously by a lever 19 and rods 20--21.

The smaller doors provide means for the discharge of the grain without opening the larger doors, or for discharging the portion of the load which comes opposite the larger doorway, in the usual manner. The upper door section 10 is also provided with an opening 22, closed by sliding doors 23--24 operating in guides 25--26 on the main door section 10, the doors held closed by a hook 27, and staple or eye 28. The upper opening provides means for the introduction of the spout whereby the grain is supplied to the car. Supported by spaced hangers 29 within the car and above the doorway opening, is a track 30 preferably in the form of a circular rod, and attached to the upper door section are brackets 31--32 having rollers 33--34 bearing upon the track. By this means the hinged door sections are supported in position to be moved longitudinally of the car, when not required.

When the improved door is to be removed from the rear of the main doorway opening, it is buckled inwardly as indicated by dotted lines in Fig. 2, and swung upwardly toward the car roof upon the track 30 as a hinge, and the lower section 11 folded beneath the upper section, or between it and the adjacent side of the car, and when the folded door sections have been moved along the track far enough to clear the frame of the doorway, they are lowered in folded positions into the space within the framing of the car between the doorway opening and the end of the car. When thus disposed the sections remain firmly in position and are held by gravity only, and require no fastenings or catches to retain them in place.

The track 30 is provided with depressions 35 where the wheels 33-34 come when the hinged door is at the terminals of its two positions, to assist in holding it and prevent dis- 5 placement by the jarring or concussions to which the car is subjected when in use. The door sections may be strengthened by additional supporting ribs as at 36-37, if required.

10 Having thus described the invention what is claimed is:—

In a car, a side provided with a doorway, a door for closing said doorway, said door consisting of two closure sections hinged together at horizontal meeting edges, each said

section having an opening at the respective upper and lower edges thereof and angle irons extending from said openings to the meeting edges of the sections, doors arranged to close said openings, a track supported above the doorway and extending beyond the side thereof, and hangers bearing mov- 20 ably upon said track.

In testimony that I claim the foregoing as my own, I have hereto affixed my signature 25 in the presence of two witnesses.

THOMAS LEONARD.
